DISPENSING DEVICE

Frank Radic, 1314 East Ave., Berwyn, Ill., and Martin Scire, 6011 W. Melrose St., Chicago, Ill.
Filed Feb. 26, 1963, Ser. No. 261,148
7 Claims. (Cl. 222—204)

This invention relates to dispensing devices for dispensing viscous materials such as toothpaste, cosmetic creams, paints and analogous materials and more particularly to a valve assembly used in such dispensing devices.

An object of the invention is to provide a dispensing device which will operate efficiently to dispense fluid and semi-fluid materials which have a tendency to clog or obstruct pumping passages because of their physical characteristics.

Another object of the invention is to provide a dispensing device having a terminal outlet which seals itself after a desired quantity of viscous material is ejected thereby preventing the material within a pumping passage from caking or drying up.

Another object of the invention is to provide a dispensing device which will operate satisfactorily in dispensing viscous materials over a relatively long distance.

A still further object of the invention is to provide a dispensing unit which can be attached to container filled with viscous substance and which is spill-proof regardless of any inverted position of the container.

An additional object of the invention is concerned with a valve assembly which is of simple construction and inexpensive to manufacture and which can be easily replaced in dispensing devices adapted to the use of this valve assembly.

Other and further objects of the present invention will become apparent from the following description and claims in reference to the accompanying drawings which, by way of illustration, show preferred embodiments for carrying out the principles involved in this invention. Other embodiments of the invention embodying the same or equivalent principles may be used and various structural modifications may be made as desired by those persons who are skilled within the art without departing from the present invention and within the scope of the appended claims.

In the accompanying drawings:

FIGURE 1 is a cross-sectional view taken along the line 1—1 in FIGURE 2 illustrating a support member which forms a component of a valve assembly shown partially in cross-section in FIGURE 6;

FIGURE 2 is a plan view of the support member;

FIGURE 3 is a plan view of a valve member forming the other component of the valve assembly shown partially in cross-section in FIGURE 6;

FIGURE 4 is a cross-sectional view taken along the line 4—4 of FIGURE 3 illustrating the valve member;

FIGURE 5 is a central longitudinal sectional view of a dispensing device embodying the present invention;

FIGURE 6 is an enlarged fragmentary section of a portion of the dispensing device shown in FIGURE 5 and illustrating the disposition of the valve assembly; and

FIGURE 7 is a central longitudinal sectional view of a modification of the invention in the form of a dispensing unit having spill-proof characteristics and which is attachable to a container filled with a fluid.

In reference to FIGURES 1 to 4, there are disclosed two components which form a valve assembly for use in the dispensing devices to be described later, said components being a support member 10 and a valve member 12. The support member 10 is in the form of a flat member of disk 14 made of rigid material and

2

having a concave surface 16 and a convex surface 18 centrally terminating in a nipple 20. One or more apertures 22 are disposed intermediate the center and the periphery of the disk 14, which is preferably made of material which is relatively inert to substances which come in contact with it during a pumping operation, as will be described later. Such inert material, for example, may be glass or stainless steel. It is to be understood that the support member may be formed into other shapes which need not necessarily be round.

The valve member 12 is made from stretchable material, relatively inert to substances with which it comes in contact during a pumping operation. For example the valve member 12 may be made from rubber, natural or synthetic. The valve member 12 has a large opening 24 and a small opening 26. The diameter of the valve member 12 is slightly smaller than the diameter of the support member 10 so that when the valve member is drawn over the support member, as shown in FIGURE 6, portion 28 of the valve member 12 tautly overlaps the aperture 22 thereby forming an effective seal thereover. Flange portion 30 of the valve member 12 stretchingly overlaps lands 32 and 34 associated with a circular groove 36 formed near the periphery of the support member 10.

The support 10 and the valve member 12 form together valve assemblies 38 and 38a which are utilized in the preferred embodiment of the dispensing device 40 shown in FIGURE 5. The dispensing device 40 has a cylindrical pumping housing 42 made of resilient material, such as rubber, and attached at one end to a connector 44 having a cylindrical external member 46 engaging an inner cylindrical member 48, for example, by threads (not shown) with the valve assembly 38 disposed between these members. The external member 46 is coupled to one end of the pumping housing 42 by any suitable means such as spring ring 50 and groove 54. The free end of the inner member 48 is coupled by suitable means, such as threads (not shown), to a collapsible container 56 filled with viscous fluid which it is desired to pump from one location to another.

The other end of the pumping housing 42 is coupled to a connector 58 which comprises a male cylindrical member 60 engaged by suitable means, such as threads 45 (not shown), with a female cylindrical member 62 with the valve assembly 38a disposed between these members.

The female member 62 is coupled to the pumping housing 42 by any suitable means, such as spring ring 64 adapted to conform with groove 66 in said female member. The 50 free end of the male member is coupled by any suitable means to tubing 68 which conducts pumped matter to a distant location and is terminated by an output unit 70 which comprises a cylindrical housing 72 with a cylindrical inlet 74 adapted for connection to the tubing 68, one end of said housing being closed by an adjustable cap 76 provided with an air vent 78, and the other end terminating in a constricted opening 80 through which pumped matter is discharged.

The housing 72 supports within itself a piston member 82 terminated at one end with a resilient nipple 84, made for example from rubber, and serving to shut the opening 80 when pumped matter ceases to flow out. The piston member 82 is urged toward the opening 80 by spring member 86 the compression of which is adjustable by the cap 76. The other end of the piston member 82 is provided with a head 88 snugly engaged with the inner wall of the housing 72 and containing an O ring gasket 90.

Reference is now made to FIGURE 6 wherein the connector 58 is shown in an enlarged view disclosing, partly in cross-section, the valve assembly 38a and its individual components, to-wit: the support member 10 and the valve member 12. The female member 62 has a ridge 92

which is adapted to overlie the groove 36 in the support member 10 and compress therebetween the flange portion 30 of the valve member 12 when the female member is forced against seat 94 on the interior of the male member.

Operation

In order to pump the viscous material within the container 56 which is made of foil or some other collapsible material, the resilient pumping housing 42 is compressed repeatedly by hand thereby expelling air out of the interior of the housing through the valve assembly 38a, the tubing 68, into chamber 96 in the output unit 70 and forcing the piston member 82 away from the opening 80 so that air can be forced out of the chamber. Specifically, as shown in FIGURE 6, air under pressure moves through a bore 98 in the female member 62 toward the valve assembly 38a, through the apertures 22 forcing the portion 28 away from its engagement with the disk 14 and the nipple 20 so that the air then moves into a bore 100 in the male member 60 and then into the tubing 68 toward the output unit 70.

During the time that the pumping housing 42 is compressed so that the valve assembly 38a operates to pass matter therethrough, the pressure built up within the housing causes the valve member 12 in the valve assembly 38 to hug more tightly its respective support member preventing thereby backup of any matter therethrough into the container 56.

Without going into too detailed explanation, it is evident that when the compression of the pumping housing 42 is removed, the housing returns to its natural unrestrained form and creating a partial vacuum in its interior thereby causing the valve assembly 38a to close and the valve assembly 38 to open and permit viscous matter within the container 56 to be drawn past the valve assembly 38 into the pumping housing 42. After the incipient air is completely expelled, the dispensing device 40 is totally filled with the pumped matter. The output unit 70 serves the function of emitting the pumped matter until no further pumping action is applied to the housing 42. Thereafter, the piston member 82 moves toward and eventually closes the opening 80 to provide an effective seal against the entry of air which could dry up the matter within the interior of the dispensing device. Also, a "wipe clean" condition is provided thereby preventing oozing and dripping of the pumped matter.

The valve assemblies described hereinbefore can be utilized in various forms of pumping devices. A modification of the dispensing device is disclosed in FIGURE 7, as identified by reference numeral 102. The dispensing device 102 comprises a housing 104, a spout 106 and a generally semi-spherical member 108 which is made of resilient material, such as rubber, and which serves as a pumping member.

The housing 104 has an outlet bore 110 with threads on the interior for engagement with threads on the exterior of the spout 106. A valve assembly 38b is placed within the bore 110 and forced against seat 112 within the bore by screwing inward the spout 106. The inlet of the housing 104 comprises a cylindrical member 114 with threads in the interior thereof adapted to engage the threads on a neck 115 of a container or glass jar 116.

Disposed on the top 118 of the neck 115, there is a resilient gasket 120, made for example of rubber, with a center opening 122 through which extends a siphon member 124 which has an outwardly flared section 126 terminating in a flange 128 which is supported atop a venting ring 130 having an air vent 132 which communicates with a groove 134 in the periphery of the venting ring. The groove 134 in turn communicates with an air vent 136 contained in the member 114 thereby, as will be described later, permitting entry of air into the interior of the container 116. A valve assembly 38c is supported atop the flange 128 and is forced against a seat 138 on the interior of the member 114 into a seal tight position

by screwing the housing 104 onto the neck 115 of the container 116. As can be readily seen, the valve assemblies 38b and 38c comprise the components as previously described in reference to FIGURES 1 to 4. The siphon member 124 extends below the level of liquid 140 in the container 116.

Operation

In order to pump the liquid 140 out of the container 116, the member 108 is compressed manually causing air or fluid contained therein to be forced through the valve assembly 38b into the spout 106 and outward through opening 142 in the spout. At this time, i.e., during the compression cycle, the valve assembly 38c is closed and there is no back flow of the fluid into the container 116.

During the relaxation cycle, i.e. when hand pressure is removed from the pumping member 108, a partial vacuum is created within the member 108 causing the valve assembly 38b to close and the valve assembly 38c to open permitting thereby the fluid 140 to be sucked upwardly through the siphon member 124, through the valve assembly 38c and into the interior of the member 108 while simultaneously outside air enters through the air vent 136, the groove 134, the air vent 132 in the vent ring 130, past the pressure seal existing between the gasket 120 and the siphon member 124, and into the interior of the container 116. In the event that the container 116 is tripped over on its side, no spilling will occur because of the pressure seal existing between the gasket 120 and the siphon member 124.

The arrangement of the valve assemblies in the embodiments disclosed in FIGURES 5 and 7 is merely illustrative. The construction of the dispensing devices may be changed to achieve any particular result. For example, the spout 106 may be constructed so that substantially no cavity exists therein so that fluid is expelled directly with no accumulation of the fluid within the spout. The position of the valve assembly 38b may be altered so that the valve assembly is substantially in contact with the sloping wall on the interior of the spout.

The present invention is not limited to the specific details set forth in the foregoing examples which should be construed as illustrative and not by way of any limitations and, in view of the numerous changes which may be effected therein without departing from the spirit and scope of this invention, it is desired that only such limitations be imposed as are indicated in the appended claims.

We claim:

1. A dispensing device comprising, in combination, an elongated compressible hollow member, a connector attached at each end of said member, each connector containing a valve assembly, one connector being adapted for attachment to a source of viscous fluid and the other connector providing a pumping outlet, each valve assembly comprising a circular support member made of rigid material having a convex surface centrally terminating in a nipple, said member having at least one aperture disposed intermediate the nipple and the periphery, a resilient circular valve member having a central opening adapted to encompass said nipple and a flange portion overlapping the periphery of said support member, the diameter of said valve member being smaller than the diameter of said support member, said valve member stretchingly overlapping said convex surface to form a seal under tension over said aperture, whereby actuation of said compressible member pumps said viscous fluid through said pumping outlet.

2. A dispensing device according to claim 1, said pumping outlet being connected to a pumping passage, and an output unit disposed at the end of said pumping passage for dispensing said viscous fluid at a predetermined minimum pressure.

3. A dispensing device comprising, in combination, a housing with a cylindrical portion adapted for attach-

ment to a container of fluid, a siphon member extending into said container and having a flange disposed within said cylindrical portion, said flange being disposed between a vent member and a valve assembly in a sealed relationship, a cylindrical spout portion in said housing, said spout portion including a spout, a second valve assembly sealingly disposed between said spout and said spout portion, each valve assembly comprising a circular support member made of rigid material having a convex surface centrally terminating in a nipple, said member having at least one aperture disposed intermediate the nipple and the periphery, a resilient circular valve member having a central opening adapted to encompass said nipple and a flange portion overlapping the periphery of said support member, the diameter of said valve member being smaller than the diameter of said support member, said valve member stretchingly overlapping said convex surface to form a seal under tension over said aperture, a pumping portion in said housing, a compressible hollow member sealingly attached to said pumping portion, and air vents in said cylindrical portion and said vent member communicating with each other and the interior of said container, whereby manipulation of said compressible member pumps said fluid out of the container past said valve assemblies out through the spout simultaneously with the entry of air through the air vents into the container.

4. A dispensing device according to claim 3, including a gasket with a central opening sealingly encompassing a peripheral portion of said siphon member and disposed adjacent said vent member atop the outlet of said container, whereby said gasket prevents leakage of fluid through said air vents.

5. A dispensing device according to claim 3, each of said valve assemblies comprising a support means with at least one opening therethrough, perforated resilient valve means stretched across one side of said support means and sealingly covering said opening, whereby said valve means prevents passage of fluid in one direction only.

6. A valve assembly for controlling the flow of pumped fluids, comprising a circular support member made of

rigid material having a convex surface centrally terminating in a nipple, said member having at least one aperture disposed intermediate the nipple and the periphery, a resilient circular valve member having a central opening adapted to encompass said nipple and a flange portion overlapping the periphery of said support member, the diameter of said valve member being smaller than the diameter of said support member, whereby said valve member stretchingly overlaps said convex surface to form a seal under tension over said aperture.

7. A valve assembly for controlling the flow of pumped viscous fluids, comprising a circular support member made of rigid material having a convex surface centrally terminating in a protuberance, said member having at least one aperture intermediate the center and the periphery of said member, a circular groove formed near the periphery and providing a pair of lands, a resilient circular valve member having a central opening adapted to encompass said protuberance, a flange portion on said valve member overlapping said lands, the diameter of said valve member being smaller than the diameter of said support member, whereby said valve member stretchingly covers said convex surface to form a seal under tension over said aperture, a pair of cylindrical connector members telescoped together and engaging said support member and said valve member therebetween, one of said connector members having a ridge adapted to press said flang portion into sealing contact with said groove.
